UNITED STATES PATENT OFFICE.

GEORGE C. SHINN, OF VANCOUVER, WASHINGTON.

HEATER FOR INTAKE-MANIFOLDS.

1,343,092.

Specification of Letters Patent. Patented June 8, 1920.

Application filed July 18, 1919. Serial No. 311,709.

To all whom it may concern:

Be it known that I, GEORGE C. SHINN, residing at Vancouver, in the county of Clarke and State of Washington, have invented new and useful Improvements in Heaters for Intake-Manifolds, of which the following is a specification.

This invention comprehends the provision of means for initially heating the intake manifold of a gas engine to facilitate starting of the motor as the fuel is heated prior to being introduced into the cylinders.

The chief characteristic of the invention resides in the provision of a casing designed to envelop the intake manifold and provided with an entrance opening through which a torch or other suitable heating means may be arranged within the casing.

In carrying out my invention, I propose to form the body portion of the casing from a single length of material and utilized from means employed for associating the intake manifold with the exhaust manifold, for holding the ends of the material in a position to form the casing.

The nature and advantages of the invention will be better understood when the following detail description is taken in connection with the accompanying drawings, the invention residing in the construction, combination and arrangement of parts as claimed.

In the drawings forming part of this specification, like numerals of reference indicate similar parts in the several views and wherein:

Figure 1 is a side elevation of a casing constructed in accordance with the invention, showing the same arranged upon the intake manifold.

Fig. 2 is a vertical sectional view taken on line 2—2 of Fig. 1.

Fig. 3 is a transverse sectional view taken on line 3—3 of Fig. 1.

Fig. 4 is a detail section taken on the line 4—4 of Fig. 1.

Fig. 5 is a view of the blank from which the casing is formed.

Fig. 6 is a view of the torch.

Before entering into a detail description, of what is herein shown, I desire to have it understood that the casing is formed from a single blank of material, which may vary in shape and size for application to any make or design of motor.

In this specific embodiment of the inven-

tion an elongated blank of material is folded transversely at a point between the ends thereof to provide the front and rear walls 10 and 11 respectively of the casing. As shown in Fig. 5 the blank of material is formed with an extension 12 projecting from one side of the material adjacent one end thereof. In the formation of the casing, this extension is carried by the rear wall 11, and is adapted to be bent around the front wall 10 to form the one side wall of the casing. This side wall terminates short of the lower end of the casing to define an opening or passage 14 for that part of the intake manifold connected to the carburetor. As shown in this instance, the opposite side of the casing is normally closed by means of a door 15, also formed from a piece of metal and given a substantially U-shaped configuration in cross section. The parallel sides 16 of the door embrace the adjacent side edges of the front and rear wall of the casing when the door is closed, the door being pivoted as at 17 so that the door can be swung to the position illustrated in Fig. 1 when it is necessary to have access to the casing.

Upon reference to Fig. 1 of the drawings it will be noted that when the device is in place the intake manifold is arranged between the front and rear walls 10 and 11 respectively, the casing being designed to completely envelop the intake manifold or substantially so. The front wall 10 adjacent its upper end is curved as at 15 in the direction of the rear wall to accommodate the pipe A, while the free ends of the material from which the casing is formed are disposed in parallelism and in contacting engagement to each other. These ends are then positioned beneath the clamps D utilized for associating the intake manifold with the exhaust manifold of the engine. In this manner, the ends of the material are maintained in proper position to form the casing. In practice, the door 15 is opened and arranged in the position disclosed in Fig. 1, to permit a torch 18 carried by one end of a wire rod 19 to be positioned within the casing. The torch 18 is of course saturated with gasoline or the like, and after the torch has been ignited, the door 15 is swung to a closed position. Consequently, the intake manifold is heated in short order by the flame of the torch, prior to starting the motor, so that when it is desired to start the

motor, the intake manifold will be hot enough to heat the fuel passing therethrough to facilitate starting of the motor. The torch burns out in a few minutes after which 5 the elements 19 are removed from the casing. In order to prevent the flame from passing through the opening 14 in the direction of the carburetor, said opening is lined with a sleeve of asbestos which surrounds 10 that portion of the intake manifold passing through said opening.

While I have shown and described what I consider the preferred embodiment of the invention, I desire to have it understood that 15 I do not limit myself to the construction, shown and described, inasmuch as such changes may be resorted to when desired as fall within the scope of what is claimed.

Having thus described my invention what 20 I claim as new is:

1. The combination with an intake manifold and an exhaust manifold of an engine, and means for securing said manifolds together, of a casing formed from a single 25 blank of material and designed to envelop said intake manifold, and the free ends of said material from which the casing is formed being arranged in parallelism and held associated by said means utilized for 30 securing said manifolds together.

2. A casing of the character described comprising a single blank of material folded between its ends to provide a front and rear wall of the casing, and an extension projecting from one side of the blank and folded to provide one side wall of the casing, a door pivotally mounted upon the front

and rear walls and designed to embrace the opposite side edges of said walls, said front wall being curved adjacent its upper end in 40 the direction of the rear wall, and the free ends of said material being arranged in parallelism and in contacting engagement.

3. A heater of the character described comprising a single length of material folded 45 between its ends into substantially U-shaped formation, one wall of the heater being perfectly straight, the outer wall being curved at a point adjacent its upper end, the free extremities of said heater being arranged in 50 face to face contact, an extension formed on the straight wall and arranged to embrace the adjacent edge of each of the walls of said heater, and a closure pivoted at its lower end and designed to embrace the opposite 55 edges of said walls as described.

4. A heater of the character described comprising a length of material bent into substantially U-shaped formation, one wall of the heater being perfectly straight, the opposite wall being curved in the direction of the straight wall and terminating to lie in parallelism with the straight wall, contacting the latter, oppositely curved projections formed on one side of the heater and 60 projecting from the respective walls thereof, an extension projecting from the straight wall and designed to embrace the adjacent edge of the other wall, a substantially U-shaped closure pivoted on said heater and 65 arranged to embrace the opposite edges of the walls for the purpose specified.

In testimony whereof I affix my signature.
GEORGE C. SHINN.
